UNITED STATES PATENT OFFICE

BERTRAND H. WAIT, OF NEW ROCHELLE, NEW YORK.

PAVEMENT AND PROCESS OF CONSTRUCTING PAVEMENTS.

Application filed March 12, 1926. Serial No. 94,212.

My invention relates to articles of manufacture made of concrete, and especially to concrete pavements and other structures such as sidewalks, platforms, driveways, floors and the like. It refers particularly to the construction of concrete slabs which should have a maximum of strength when considered as a beam, but in which it is desirable that the upper or wearing course

5 should be removable or replaceable without the necessity of removing the entire depth of slab.

Concrete pavements have heretofore been constructed in layers which are entirely separated from each other by means of intermediate courses of varying character, and in which the upper or wearing course, by reason of this separation or independence, is easily removable. Two course pavements

10 have likewise been constructed in which the courses have been laid at substantially the same time and worked together to form a monolithic structure. Concrete pavements

15 of the first class, in which the courses are independent are not as strong as a monolithic structure of the same depth. They have the advantage of a removable wearing course, but this course, which acts as a beam

20 more or less independently of the lower course, must be constructed of comparatively great thickness to produce satisfactory results. On the other hand, pavements of the

25 second class, while structurally stronger than pavements of the first class mentioned, do not possess the advantages inherent to a removable top course.

My invention therefore, in its broad aspects, contemplates a monolithic pavement or the like and the method of constructing

30 the same whereby the entire slab will act as an integral beam but in which the upper or wearing portion will be readily cleavable from the lower or base portion so that it may be removed when necessary without

35 damage to the lower portion.

The objects of my invention are to provide a pavement and a method of constructing the same as an integral, monolithic slab which will have all of the advantages in

40 beam strength of such a slab, but in which a predetermined stratum is provided along which the upper and lower portions of the pavement are readily separable. Another object of my invention is to provide a

45 method by which a complete two layer pavement of this character may be constructed

by a continuous operation, thereby effecting great economy in time and labor. Still another object of my invention is to provide a concrete pavement in which the maximum quantity of low grade aggregate and the minimum quantity of high grade aggregate and cement may be used, thereby effecting a great saving in the cost of materials.

With these objects in view my invention includes the hereinafter described process and pavement, an embodiment of which is illustrated in the accompanying drawings in which—

Fig. 1 is a typical, small scale cross section of my pavement;

Fig. 2 is an enlarged fragmentary section of the lower course illustrating the preferred method of preparing for the reception of the upper course;

Fig. 3 is a section similar to Fig. 2 illustrating a lower course prepared in a slightly different way for the reception of the upper course;

Fig. 4 is a plan view illustrating in a more or less typical way the fabric which I prefer to incorporate in my pavement; and

Fig. 5 is a highly magnified fragmentary section of the cleavage stratum.

Referring to the drawing, 1 represents the lower course, 2 represents the upper course, and 3 represents an intermediate course of fabric.

In constructing my pavement the lower course is first laid upon the subgrade or other foundation and, according to my preferred method, is worked or manipulated by methods well known in the art so that a thin layer of mortar, 4, is brought to the surface. Upon this mortar surface is laid a fabricated medium, 3, which is pervious to mortar but substantially impervious to coarse aggregate, and which, for reasons hereinafter mentioned, I prefer to embed slightly in the mortar, or at least to press slightly by a light roller or otherwise, so that the mortar is forced therethrough. The upper course is then placed immediately and before the lower course has attained its initial set, and the surface is finished by the usual methods.

The medium which I propose to use may be of almost any character provided it will divide a stratum of the concrete into a multiplicity of spaced, comparatively small or minute areas, 5. For example, ordinary cheese cloth, which is cheap, gives very satis-

factory results, and any fabric or fabricated medium such as metal screen, cloth, burlap or the like having comparatively small, closely spaced interstices which will permit an integral mortar bond between the concrete on either side thereof and yet give the desired cleavage may be employed. The interstices or perforations in the medium should be of such size that the coarse aggregate cannot project therethrough thus providing an interrupted stratum of mortar alone which is comparatively weak. In connection with the general character of the medium which I propose to employ, it is to be understood that the purpose of this invention is not to strengthen or reinforce the monolith but to render it susceptible to splitting along a predetermined surface or stratum without otherwise substantially affecting its strength. In other words, the medium which I propose to incorporate is of such character that it weakens rather than reinforces the concrete. Hence the structural strength of the medium itself is substantially immaterial and for economical reasons is preferably light in weight and of slight structural strength.

Breaking tests have indicated that the concrete is readily cleavable along the plane of fabric and it appears that this results from the separate breaking of the closely spaced minute areas of integrity, 5, between the courses so that the splitting is progressive in character across the zone or stratum of cleavage. On the other hand, breaking tests have demonstrated that a beam constructed with such a cleavage stratum therein has the full strength of a beam of the same depth and without the cleavage stratum. The reasons for this are that the actual area of the strands of fabric is only a small percentage of the total area along the plane of the fabric and there is a matrix contact between the upper and lower courses for a large percentage of the area of said plane. On the other hand, the matrix is divided into a multiplicity of very small integral parts by the strands of the fabric, and these small parts or sections break one by one when the monolith is split or cleft.

In constructing my pavement the aggregate or mix of either course may be varied as desired. However, it is obvious that cheap, low grade aggregate and a comparatively lean mixture may be used in the lower course. By manipulating this course so as to bring the mortar to the surface, and slightly embedding the fabric in this mortar, the cleavage plane will be located in a zone of comparatively weak matrix so that separating will be facilitated. On the other hand, slightly embedding the fabric stiffens up the lower course so that the upper course will not be worked into it. In this way the upper course can be built of a uniform depth and consistency, thus eliminating hair

checking and initial cracking due to uneven depth of upper course. It is to be understood that my process is not in any sense limited to the embedding of the fabric in the surface of the lower course or to working the lower course to produce a mortar surface thereon. While I believe the best results are obtained in that way, it is obvious that the fabric may be merely laid upon the lower course either with or without manipulating the lower course to produce a mortar surface.

It is also to be understood that my invention is not limited to use in connection with concrete comprising coarse aggregate but may be used with good results in a pavement of mortar alone.

One very great advantage of my pavement over either a one or two course pavement as heretofore constructed resides in the fact that the upper course may be quite thin, and may be laid comparatively dry and of rich mixture. The amount of manipulation required by such a course is much less than that required by present methods and types of construction and, because of the intermediate fabric, no poor materials will be worked to the top and cause scaling.

My pavement may, of course, be laid with expansion and contraction joints, with steel or other reinforcement, either in the top or bottom or both, and of any mixture or depth, all as required by the traffic, temperature variations, subgrade and other conditions affecting the design as a structure.

While I have described my invention as particularly applicable to the construction of pavements it is obvious that the invention herein disclosed will be useful in the concrete art generally and it is to be understood that I am not limited in its application to pavements or the like. It is also to be understood, that the words which I have used in describing my invention and its application are words of description and not of limitation, and that changes within the purview of the appended claims may be made without departing from the scope and spirit of this invention.

What I claim is—

1. The process of constructing a monolithic pavement or the like having a stratum therein along which the monolith may be cleft or split, which comprises placing a course of concrete, working the same to produce a mortar surface thereon, placing on said surface a fabricated medium pervious to mortar but substantially impervious to coarse aggregate, and placing thereover a second course before the setting of the first course.

2. The process of constructing a monolithic pavement or the like having a stratum therein along which the monolith may be cleft or split, which comprises placing a course of concrete, working the same to pro-

duce a mortar surface thereon, embedding in said surface a fabricated medium pervious to mortar but substantially impervious to coarse aggregate, and placing thereover a second course before the setting of said mortar.

3. The process of constructing a monolithic pavement or the like having a stratum therein along which the monolith may be cleft or split, which comprises placing a course of concrete, placing thereon a fabricated medium pervious to mortar but substantially impervious to coarse aggregate, and placing a second course of concrete thereon before the setting of the first course.

4. The process of constructing a monolithic pavement or the like having a predetermined stratum therein along which the monolith may be cleft or split, which comprises permanently embedding in said monolith and substantially coextensive with the cleavage stratum desired, a fabricated medium pervious to mortar but substantially impervious to coarse aggregate.

5. In a concrete pavement or the like, a fabricated medium intermediate the upper and lower surfaces thereof having no appreciable reinforcing effect, but dividing the matrix in the zone of said medium into a

multiplicity of spaced sections of comparatively small area, whereby is formed a stratum of weakness along which the concrete may be cleft or split.

6. A concrete pavement or the like, having a stratum of mortar therein divided into a multiplicity of spaced, comparatively small areas of integrity with the concrete on either side of said zone, whereby is created a weakened section along which the concrete may be split or cleft.

7. A substantially monolithic concrete pavement or the like having a mortar pervious fabric of slight structural strength embedded therein and forming a stratum of comparative weakness along which the concrete may be cleft or split.

8. A monolithic concrete pavement or the like having embedded therein a fabricated medium pervious to mortar but substantially impervious to coarse aggregate, forming a stratum of comparative weakness along which the monolith may be cleft or split.

9. A monolithic concrete pavement or the like having a layer of cheese cloth embedded therein and forming a stratum along which the monolith may be cleft or split.
